CLAIM

The ornamental design for a multi-channel pet treat, as shown and described.

DESCRIPTION

FIG. 1 is a top, front and right perspective view of a multi-channel pet treat according to our new design; FIG. 2 is a top plan view thereof; FIG. 3 is a bottom plan view thereof; FIG. 4 is a front elevational view thereof, with a rear elevational view being a mirror image thereof; and, FIG. 5 is a right side elevational view, with a left side elevational view being a mirror image thereof.

(Continued)

The stippling shown in FIGS. 1, 2 and 4 illustrates a contrasting appearance for a filling portion of the multi-channel pet treat.

1 Claim, 5 Drawing Sheets
